WHEAT SHOCKER

William M. Walburt, Altus, Okla., assignor of
one-half to Doyle F. Pair, Altus, Okla.

Application December 7, 1932. Serial No. 646,162

4 Claims. (CL 56—405)

This invention relates to shockers, especially adapted for operation in connection with binders and similar machines and has for the primary object, the provision of a device to receive and collect bundles from the binder, with means whereby bundles after having been grouped in desired numbers may be discharged onto the ground and left remaining in a stacked position to form the usual shock to be collected later or when desiring to thrash the grain.

Another object of the invention is the provision of a device of the above stated character which may be easily attached to a binder for movement therewith and which may be easily operated manually to dump or discharge the stacked bundles in shocked formation on the ground.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating a shocker applied to a fragmentary portion of a binder and constructed in accordance with my invention.

Figure 2 is a plan view partly in section illustrating the shocker.

Figure 3 is a transverse sectional view taken on the line 3—3 of Figure 1.

Figure 4 is a similar view taken on the line 4—4 of Figure 1.

Figure 5 is a fragmentary plan view illustrating the jaws positioned ready to release a number of bundles in stacked formation to form a shock.

Figure 6 is a detail sectional view illustrating stops for limiting the movement of the jaws.

Figure 7 is a detail view partly in section illustrating one position of the bundle adjusting arm.

Figure 8 is a similar view showing the other position of said arm.

Referring in detail to the drawings, the numeral 1 indicates an elongated frame having one end hinged to a binder 2 directly under the delivery table or chute 3 of the latter and the frame 1 is further supported by ground wheels 4 and 5. The ground wheel 5 is located at the forward side of the frame while the ground wheel 4 is located rearwardly of the rear

side of the frame and is journaled between a pair of arms 6 which extend rearwardly from the frame. The mounting of the wheel 5 is journaled to the frame so that the wheel 5 will readily follow the course taken by the frame when traveling with the binder and the hinged connection between the frame 1 and the binder permits the frame 1 to move upwardly and downwardly with respect to the binder when passing over uneven ground. The outer end of the frame 1 carries a table 7 provided at its receiving edge with an extension 8 terminating adjacent the discharge end of a conveyor 9, the receiving end of the latter being disposed under the table or chute 3. The conveyor 9 is of the endless type having sprocket chains 10 traveling on sprocket wheels 11 secured to shafts 13 journaled in bearings 14 on the frame 1. One of the shafts 13 is of greater length than the remaining shafts and extends rearwardly between the arms 6 and has secured thereto a pinion 15 which meshes with the beveled gear 16 secured to the ground wheel 4 so that the latter may impart movement to the conveyor during the travel of the frame with the binder. Substantially U-shaped brackets 17 are secured to the conveyor and arranged transversely thereof and each bracket being of the stated shape provides spaced arms 18 equipped with apertured ears 19 in which L-shaped rods 20 are journaled. The rods 20 of each bracket oppose each other and are arranged transversely of the conveyor and are yieldably retained in this position by springs 21. The purpose of the rods 20 is to engage bundles received on the conveyor and cause said bundles to move with the conveyor onto the extension 8 of the table 7, the extension 8 projecting between the arms of each bracket 17 as the latter passes from the upper run of the conveyor to the lower run at the discharge end of the conveyor. When the rods 20 are engaged by the extension 8 of the table they swing upon their hinges so as to pass the extension. The rods 20 which are arranged in pairs provide yieldable flights to the conveyor capable of resisting the bundles so as to compel the latter to move with the conveyor.

Frames 22 are arranged at opposite sides of the frame 1 between the discharge chute 3 of the binder and the table 7 and one of the frames is provided with a guide rail 23, while the other frame is provided with a guide rail 24. The guide rails are arranged inwardly over the upper run of the conveyor and said guide rails toward the receiving end of the conveyor diverge.

- The guide rails over the extension 8 of the table converge for the purpose of retarding the movement of a bundle when in engagement with the extension 8 of the table. The diverging end of the rail 24 terminates short of the diverging end of the rail 23 and is engaged by a trip arm 25 pivoted to the frame 1 and carrying a roller 26 adapted to ride upon the upper run of the conveyor, the conveyor being provided at spaced intervals with cam-shaped lugs 27 to engage the roller 26 to cause a swinging movement of the trip arm 25. The roller when in engagement with the conveyor causes the arm 25 to maintain a position to cooperate with the rail 23 in receiving a bundle in a horizontal position from the chute 3 of the binder and when the roller 26 is engaged by one of the cam-shaped elements 27 the trip arm 25 is rocked freeing the butt end of the bundle so as to engage with the upper flight of the conveyor with a pair of the rods 20 in engagement therewith, causing the bundle to move with the conveyor in a vertical position between the guide rails 23 and 24 until the butt end of the bundle passes onto the extension 8 of the table whence the upper end of the bundle is retarded by the converging portions of the rails 23 and 24, causing the bundle to assume an inclined position, as shown in Figure 1, due to the pair of rods in engagement therewith passing downwardly at the discharge end of the conveyor. This bundle retains the stated position until engaged by a following bundle, whence the latter is shoved onto the table 7 between a pair of pivotal jaws 28. The jaws 28 are of arcuate formation pivoted to ears 29 secured to a vertically arranged shaft 30 located on a sub-frame 31 carried by the outer end of the frame 1. The shaft 30 is journaled to the sub-frame and the jaws are normally urged towards each other by springs 32. The jaws at their pivots are provided with stops 33 and 34. The purpose of the stops is to limit the movement of the jaws towards each other and away from each. The bundles collected in the jaws, the latter slightly yield so as to accommodate a plurality of bundles in stacked formation on the table and secured to the shaft 30 is an arm 35 to which is pivoted a control lever 36 whereby the operator on the binder may rotate the shaft for swinging the jaws outwardly on the table carrying with said jaws the stacked bundles. An arm 37 is connected to the pivoted end of one of the jaws and is in turn pivoted to a control rod 38 whereby the operator on the binder may swing one of the jaws away from the other jaw to release the stacked bundles upon the ground in shocked formation. The delivery of the stacked bundles from the table onto the ground may be accomplished rapidly by the operator so that the jaws can return to a position over the table ready to receive the following bundles from the conveyor.
- While I have shown and described the preferred embodiment of my invention, it will be understood that minor changes in construction, combination and arrangement of parts may be made without departing from the spirit and scope of my invention, as claimed.
- Having described the invention, I claim:
1. A shocker comprising a frame connected to and movable with a binder, a conveyor carried by said frame and having receiving and discharge ends, means for driving said conveyor, guide rails on the frame and disposed over the conveyor and having diverging ends and converging ends,

a trip arm carried by the frame and cooperating with one of the guide rails in receiving bundles from the binder in horizontal position, means for actuating the trip arm to release the bundles onto the receiving end of the conveyor in an upright position between the guide rails, and means at the discharge end of the conveyor to receive and collect a plurality of bundles on the table and to move the collected bundles off of the table onto the ground in shocked formation.

2. A shocker comprising a frame connected to and movable with a binder, a conveyor carried by said frame and having receiving and discharge ends, means for driving said conveyor, guide rails on the frame and disposed over the conveyor and having diverging ends and converging ends, a trip arm carried by the frame and cooperating with one of the guide rails in receiving bundles from the binder in horizontal position, means for actuating the trip arm to release the bundles onto the receiving end of the conveyor in an upright position between the guide rails, a table on the frame, an extension on the table and terminating adjacent the discharge end of the conveyor to receive the bundles therefrom, means located above the table to receive the bundles on the table and to swing a predetermined number of bundles off of the table onto the ground in shocked formation.

3. A shocker comprising a frame connected to and movable with a binder, a conveyor carried by said frame and having receiving and discharge ends, means for driving said conveyor, guide rails on the frame and disposed over the conveyor and having diverging ends and converging ends, a trip arm carried by the frame and cooperating with one of the guide rails in receiving bundles from the binder in horizontal position, means for actuating the trip arm to release the bundles onto the receiving end of the conveyor in an upright position between the guide rails, a table on the frame, an extension on the table and terminating adjacent the discharge end of the conveyor to receive the bundles therefrom, said converging portions of the rails adapted to cause a retarding of the movement of each bundle at the upper end thereof when the lower end contacts with the extension, means on the conveyor to engage each bundle and cause movement thereof with the conveyor, each bundle when left on the extension in an inclined position by the conveyor adapted to be shoved onto the table by the following bundle from the conveyor, and means operable above the table to collect a series of bundles and swing them off of the table and deliver them onto the ground in shocked formation.

4. A shocker comprising a frame connected to and movable with a binder, a conveyor carried by said frame and having receiving and discharge ends, means for driving said conveyor, guide rails on the frame and disposed over the conveyor and having diverging ends and converging ends, a trip arm carried by the frame and cooperating with one of the guide rails in receiving bundles from the binder in horizontal position, means for actuating the trip arm to release the bundles onto the receiving end of the conveyor in an upright position between the guide rails, a table on the frame, an extension on the table and terminating adjacent the discharge end of the conveyor to receive the bundles therefrom, said converging portions of the rails adapted to cause a retarding of the movement

of each bundle at the upper end thereof when the lower end contacts with the extension, means on the conveyor to engage each bundle and cause movement thereof with the conveyor, each bundle when left on the extension in an inclined position by the conveyor adapted to be shoved onto the table by the following bundle from the conveyor, and pivotally mounted and yieldable

jaws located above the table to receive the bundles on the table in grouped formation and manually controlled means for swinging the jaws to position the collected bundles laterally of the table, and means for spreading the jaws to release the collected bundles carried thereby for deposit onto the ground in shocked formation.
